UNITED STATES PATENT OFFICE.

WILLIAM C. MOTTERAM, OF PHILADELPHIA, PENNSYLVANIA.

TANK FOR DEVELOPING PHOTOGRAPHIC FILMS.

1,302,408.

Specification of Letters Patent.

Patented Apr. 29, 1919.

Application filed August 22, 1917. Serial No. 187,636.

To all whom it may concern:

Be it known that I, WILLIAM C. MOTTERAM, a citizen of the United States, residing in Philadelphia, county of Philadelphia, 5 State of Pennsylvania, have invented certain new and useful Improvements in Tanks for Developing Photographic Films, of which the following is a specification.

My invention relates to tanks or receptacles adapted to receive means for holding the films in spaced relation to each other while being treated with the developing solution which may be introduced into the tank or receptacle after the films have been 15 placed therein and properly spaced.

The objects of my invention are to provide a tank which may be satisfactorily used for the development of films without resorting to a "dark room"; to provide 20 means in the tank whereby a portion of the casing of the film pack is torn from other portions to permit the withdrawal of the films from the pack after the same has been partially inserted into the tank; to provide 25 a holder for the film which holder is provided with means for engaging one end portion of one side of the cover pack, which engaging portion engages means within the tank as the said holder is inserted thereinto 30 for causing lateral movement thereof and thereby effecting the tearing apart of portions of the film pack casing to permit the withdrawal of the films therefrom; to provide means for supporting and holding the 35 films in fixed spaced relation with respect to each other within the tank while the treatment by the developing solution is taking place; and also to provide means for effecting a clamping and unclamping action 40 of portions of the said holding means as desired.

Other objects and advantages of my invention will be referred to in the detail description thereof which follows or will be 45 apparent from the same.

In order that my invention may be more readily understood and its practical and commercial advantages more fully appreciated and comprehended reference should 50 be had to the accompanying drawings in which I have illustrated one form of a convenient embodiment thereof. However, it will be understood that my invention is sus-

ceptible of embodiment in other forms of construction than that shown.

55

In the drawings:—

Figure 1 is a view showing the tank in longitudinal section and the holding means together with a film pack holder and film pack partially inserted into the said tank in 60 side elevation;

Fig. 2 is a sectional view taken on the line 2—2 of Fig. 1, one side of one end portion of the film pack holder employed for holding the film pack as it is inserted into 65 the tank being shown in elevation;

Fig. 3 is a view similar to that shown in Fig. 1, but with the film pack holder and means for holding the films in the tank occupying different positions therein;

70

Fig. 4 is a top plan view of the means for holding the films in spaced relation to each other and which is adapted to be inserted into the tank;

Fig. 5 is a transverse sectional view taken 75 on the line 5—5 of Fig. 4;

Fig. 6 is a sectional view taken on the line 6—6 of Fig. 4;

Fig. 7 is a view showing the bottom part of the device for holding the films in spaced 80 relation to each other in the tank partly in transverse section and partly in top plan view;

Fig. 8 is a central longitudinal section of the lower portion of the film pack holder 85 and of a film pack therein showing the end portion of one side of the film pack casing torn away to permit the withdrawal of the films therefrom; and

Fig. 9 is a sectional view of a portion of 90 the top part of the device for holding the films in spaced relation to each other in the film tank taken on the line 9—9 of Fig. 4.

Referring to the drawings, 1 designates a casing of suitable material which is adapted 95 to receive a film pack and also a device for holding the films of the pack holder in spaced relation to each other while the same are being treated with the developing solution.

100

The upper end of the casing is provided with a laterally extending portion 2 which constitutes a supporting shoulder for a purpose to be hereinafter described. 3 designates a portion of the casing of the tank 105 extending a short distance upwardly from

the outer edge of the laterally extended portion 2.

5 designates portions situated upon two sides of the tank in opposing relation to each other. The upper and lower ends of these portions rest against the said sides while the remaining portions of the said parts 5 are spaced from the said sides. These portions 5 consist of plates which 10 may be supported in any desired manner in the positions shown. They are each provided with slots as shown, the said slots respectively comprising upper portions 8 which extend parallel to the sides of the 15 casing 1 and inclined portions 9 which extend inwardly; that is, toward a plane through the center of the tank parallel with the plane through the portions 8 of the said slots. Below the portions 9 of the said 20 slots are portions 10 also parallel or substantially parallel with the sides of the casing of the tank but which are situated farther inwardly than are the portions 8 of the said slots. 11 designates outwardly inclined portions of the said slots, the lower ends of which terminate at points substantially in line with the portions 8 thereof.

12 designates a cover for closing the top of the casing 1. It is necessary to use such 30 cover if it is desired to turn the tank upside down during the time that the films are being treated with the developing solution, but as will hereinafter appear, if the tank is kept in an upright position the use 35 of the cover 12 may be dispensed with.

Referring now to the device which is used for inserting or placing the films within the casing of the tank and for holding the said films in spaced relation to each other after 40 having been so inserted, 20 designates a frame of square, rectangular or other outline as may be desired which frame is provided with oppositely disposed sides 21 of channel shape, which channels face each 45 other. 22 designates a plurality of clamping bars, which, in the construction shown, are curved but instead of being curved they may be of other shape and still be within the scope of my invention. The opposite 50 ends of these bars are reduced to form portions 23 which fit between the flanges of the channels of the sides 21. It is apparent that these clamping bars 22 are slidable toward and from each other in these channels. Of 55 the opposing sides of the frame 20 connecting the channel sides 21, one of them, 24, is curved to conform to the curvature of the curved clamping bars 22. To the inner curved surface of the curved side 24 a correspondingly curved plate 25 is secured the 60 inner surface or side of which co-operates with the next adjacent clamping bar for holding a film which may be interposed there-between. The side 26 of the frame 20 opposite the side 24 thereof is straight as

shown. 27 designates a plate similar to the plate 25 except that the said plate 27 is slidably supported at its opposite ends in the channels of the channel sides 21. The plate 27 is curved to correspond to the curvature 70 of the adjacent clamping bar and co-operates therewith to clamp and hold the film which may be interposed there-between.

30 designates plate spring members which are adjustably secured by means of pin and 75 slot connections as shown at 31 to the side 26. The outer ends of these springs are bent inwardly to form spring contacting portions which contact with the opposing adjacent portions of the curved plate 27 to hold the 80 same in binding relation against the adjacent clamping bar and also to hold the remaining clamping bars in clamping contact relation with respect to each other. By moving these spring members 30 inwardly 85 the clamping members are permitted to be separated both to permit the insertion of the films and "tabs" of the films between the said clamping bars and to permit the cleansing and drying of the opposing surfaces of 90 the said clamping bars. 33 designates a bail secured at its opposite ends to the channel sides of the frame 20. The frame 20, together with the clamping bars, etc. supported thereon, is referred to and may be regarded as the bottom part of the film holding 95 device.

Slidably connected with the opposite sides or legs of the bail 31 is a top film clamping and holding part, said part comprising a 100 plate 35, the edges of which upon three sides thereof, when the film clamping and holding device is in position within the tank casing 1, are adapted to rest upon the shoulder formed by the laterally extending 105 flanges 2. Oppositely disposed angle plate members are provided, said members in transverse section each comprising a vertically disposed portion 36, an inwardly extended flange portion 37 and an outwardly 110 extended flange portion 38, the latter portions constituting convenient means for securing the said members 36 to the underside of the plate 35.

40 designates clamping bars curved in the 115 construction shown, as are the clamping bars 22, but which may be of other shape if desired. The opposite ends of these clamping bars rest upon and are supported by the oppositely disposed inwardly extending 120 flanges 37. The said clamping bars 40 are provided with shoulders, as indicated at 41, the said shoulders, together with the intermediate portions of the said bars, projecting through an opening 42 in the plate 35 a distance above the upper surface of the latter. 45 designates a plate secured upon the upper surface of the plate 35, said plate having an opening 46 therethrough corresponding to and in registry with the opening 42, and the 130

said plate also being provided with projections 47. Said projections and the portions of the plate 35 thereunder are provided with holes 48 through which the sides of the bail 5 33 extend.

50 designates a curved metallic plate co-operating with the adjacent opposing clamping bar 40 and being rigidly secured to the inner edges of one side of the openings 42 and 46 through the plates 35 and 45. 51 designates a curved metallic plate situated in oppositely disposed relation to the plate 50. The opposite ends of the said plate rest and slide upon the flanges 37.

15 As a means for adjusting the said clamping bars toward each other and for permitting separation thereof I have provided a cam plate 53 situated between adjacent edge portions of the plates 35 and 45 at the opposite edge portions of said plates from those to which the curved plate 50 is connected. The curved plate 51 is secured to the inner curved edge of the cam plate 53. For the purpose of adjusting the said cam plate I 25 have provided the same with an opening 55 against the edges of which an eccentrically supported cam member 56 is adapted to contact to cause positive movement of the said plate 53 in one direction to force the said 30 clamping bars toward each other into clamping relation to each other and to permit movement thereof in the opposite direction so as to allow the "tabs" of the films to be inserted between the said bars. The said 35 cam 56 is supported upon a shaft or pin 60 which is pivotally supported in the portions of the plates 35 and 45 upon opposite sides of the plate 55. 61 designates a handle by means of which the said shaft or pin 60 may 40 be rotated to actuate the said cam.

The bail 31 fits the openings 48 closely so that the top member of the film holding device will remain in whatever position upon the said bail to which it may be adjusted.

45 The plate 35 is provided with a cut out portion 70 at one edge forming projections 71. 73 designates a plate secured to the underside of the edge portion 74 of the plate 35. Said plate 73 is provided with outwardly extending projections 75 at its opposite ends situated directly underneath the inner edge portions of the projections 71. The space between the projections 71 and the projections 75 is provided for receiving the 55 film pack holder 80, said holder being guided in its movement downwardly into the tank to the position shown in Fig. 3 of the drawings between the projections 75 and the inner edges of the projections 71. Said holder 60 is of a size and shape to hold the said pack snugly.

The said film pack holder is provided at one end with an extension 81 having hinged connection at 82 with the edge of one side of 65 the said holder. Adjacent to its lower outer

edges the said extension is provided with inwardly extending hooked portions 83 which are adapted to be engaged with end portions 84 of one side of a film pack casing, as shown in Fig. 8 of the drawings.

70

85 designates projections at the outer ends of the opposite edges of the extension 81, said projections being provided with openings 87 in which the opposite ends of a rod 88 are mounted, preferably revolvably. The 75 said rod is thicker at its middle than at other portions thereof and tapers from its middle toward its opposite ends.

The films as they are drawn from the pack pass under and in contact with the rod 88 which causes the said films to be initially bent transversely to correspond with the bend or curvature of the clamping bars or members 22 and 40 heretofore described.

When it is intended to use a device constructed in accordance with my invention for developing films the film packs are used in the usual way in the camera and by means of the "tabs" are pulled forwardly within the pack, but instead of tearing off the "tabs" as 90 is now the practice the said "tabs" are allowed to remain. When it is desired to develop the films in a tank constructed in accordance with my invention the film pack may be inserted within a holder 80 and the 95 hook-like portions 83 engaged with portions of a side at the opposite edges of one end thereof and thereafter the "tabs" may be inserted through the spaces intermediate the clamping bars 22 and the co-operating clamping plates 25 and 27 and thence through the spaces intermediate the clamping bars 40 and the clamping plates 50 and 51 in the upper part of the film holding device. The 100 "tabs" are extended a short distance beyond the upper side of the top part of the said device, as shown in Fig. 1 of the drawings, and are clamped in such position by actuation of the cam 56 to force the clamping devices into holding clamping relation with respect to 105 each other. It may be noted also that at this time the springs 30 are moved outwardly into position to hold the clamping bars and plates 22, 25 and 27 in the lower part of the said device in relatively close relation with 110 respect to each other so as to properly maintain the films there-between. It will be understood, of course, that the order of procedure may be changed or varied without in any way affecting my invention.

115 After the said "tabs" have been inserted into the position between the bars of the upper and lower parts of the holding device the said holder 80 is turned around into the position indicated in Fig. 1 of the drawings 120 in the space between the projections 75 and the inner edges of the projections 71 and the said film holding device and the said holder 80 are then inserted into the top of the casing 1 of the receptacle so that the edges of 130

125

the top plate 35 rest upon the shoulder formed by the laterally extended part 2 of the casing. The holder 80 is then moved downwardly, the opposite projecting ends of the guide rod 88 projecting into the slots 8. Engagement of these ends with the inwardly inclined portions 9 of these slots forces the said rod, together with the outer lower end of the hingedly supported part 81, inwardly 10 to the position shown in Fig. 8 of the drawings. Such inward movement, by reason of the engagement of the hooked portions 83 with end portions of one side of the film pack casing disconnects the adjacent end portion of said side from the said film pack casing and bends the same laterally, as is shown in Fig. 8 of the drawings. When the film pack holder 80 has been moved downwardly so that the opposite ends of the rod 88 occupy positions at the lower ends of the inwardly inclined portions 9 of the slot further downward movement is temporarily discontinued. The cam 56 is then released and the films are pulled forwardly between 15 the clamping bars as far as they will go, which is until the shoulders 90 of the said films intermediate the same and the "tabs" 91 contact with the underside of the plate 35, as shown in Fig. 6 of the drawings. Thereafter the cam 56 is operated to again clamp the films between the clamping bars and plates 40, 50 and 51. Thereafter the film pack holder is moved downwardly until the opposite ends of the rod 88 reach the lower 20 ends of the outwardly inclined portions 11 of the said slots. Thereafter the bail, to the lower ends of which the lower part of the film holding device is connected, is moved downwardly, such movement causing downward movement of the lower part of said device into the position shown in Fig. 3 of the drawings adjacent the bottom of the tank casing 1. It will be seen, therefore, that the films are supported in spaced parallel relation with respect to each other within the tank casing and also that they are curved to conform to the curvature of the clamping bars of the upper and lower parts of the holding device.

25 The parts having been placed in the positions within the tank casing as shown in Fig. 3 the developing solution may be charged into the tank casing through the film pack casing within the film pack holder 80 by opening the upper end of the said film pack casing which may be readily done as is well known. Such developing solution runs down through the film pack casing and holder 80, entering the tank near the bottom 30 thereof and gradually filling the same to completely submerge and surround the films supported therein.

35 The presence of the top part of the film holder within the tank, the film pack holder and of the film pack casing within the said

last mentioned holder is sufficient to shut out the light from the interior of the said tank as completely as is necessary for effectively developing the films. This being the case the cover 12 is unnecessary unless it be desired to turn the tank upside down during the time that a developing operation is proceeding.

I claim:—

1. In a device of the character described, 75 the combination of the casing of a tank for developing photographic films, a holder for holding the casing of a package of films, said holder being provided with movable means for engaging a part of the said package casing, means within the said tank casing for engaging the said movable means to cause lateral movement thereof for the purpose described.

2. In a device of the character described, 80 the combination of the casing of a tank for developing photographic films, a holder for holding a package of films which are adapted to be inserted into the casing of said tank, one side of said holder having an extension pivotally connected therewith and means within the casing of the said tank for engaging said pivoted extension to cause pivotal movement thereof as the said holder is inserted into the said tank, substantially as 90 and for the purpose described.

3. In a device of the character described, 95 the combination of the casing of a tank for developing photographic films, said casing being provided with a cam situated interiorly thereof, a holder for receiving and holding a film pack casing, one side of the said holder being provided at one end with a pivoted extension, said extension being provided with means for engaging the end 100 of one side of the said film pack casing, and means upon the said extension which is adapted to engage the said cam whereby lateral movement of the said extension is effected to cause separation of a portion of the 105 said side of said film pack casing from other portions thereof, substantially as and for the purpose described.

4. In a device of the character described, 110 the combination of the casing of a tank for developing photographic films, members situated in oppositely disposed relation to each other against opposing sides of the said casing, which members are provided with cam slots, a holder adapted to receive and 115 hold photographic film pack casings, one side of said holder being provided at one end with a hinged extension, said extension being provided with means for engaging opposite edge portions at one end of one side of 120 the said film pack casing, said holder being adapted to be inserted within the said tank casing intermediate the members aforesaid, and means upon the said extension for engaging the said cam slots whereby 125 lateral 130

movement of the said extension is caused as the said holder is moved downwardly into the casing of said tank, substantially as and for the purpose described.

5. In a device of the character described, the combination of the casing of a tank for developing photographic films, plates situated in opposing relation to each other in adjacent relation to opposing sides of said 70
10 casing, said plates being provided with slots having top vertical portions, intermediate inwardly inclined portions, intermediate vertical portions and bottom outwardly inclined portions, a rectangular holder for receiving 75
15 and holding a rectangular film pack casing, one side of said holder being provided at one end with a hinged plate extension, said extension being provided with hook portions upon its outer edge, said hook portions being 80
20 adapted to engage the adjacent end edge portion of one side of the said film pack casing, and means upon the said extension which are adapted to engage the said slots as the said film pack holder is inserted into the said 85
25 tank casing, substantially as and for the purpose described. 90
6. In a device of the character described, the combination of the casing of a tank for developing photographic films, a film pack 95
30 holder adapted to be inserted within the said casing, said holder being provided with movable means having devices adapted to engage one end of one side of the casing of the said film pack, means within the said 100
35 tank casing for engaging a part of the said movable means to cause lateral movement thereof as the said holder is inserted within the said tank, such lateral movement being adapted to cause a breaking open of a portion 105
40 of one side of the said film pack casing to permit the withdrawal of films therefrom and a holding device for holding the said films in spaced relation with respect to each other within the tank casing after 110
45 they have been withdrawn from the film pack. 115
7. In a device of the character described, the combination of the casing of a tank for developing photographic films, a holder for 120
50 a casing containing films, which holder is adapted to be inserted within said tank casing, one side of said holder being provided at one end with a hinged extension, said extension being provided with means for engaging one end of one side of the said film-contain- 125
55 ing casing, means within the said tank casing for engaging the said extension to cause lateral movement thereof to tear apart the portion of the said film-contain- 130
60 ing casing with which the said hinged extension is in engagement and the said extension being provided at its outer edge with a rod under which the films pass as they are drawn from the film pack casing and a hold-
65 ing device for receiving the said films as

they are withdrawn from the said film pack casing after the same have been inserted within the tank casing, said holding device comprising two sets of clamping bars between which the said films are adapted to be held in spaced relation to each other, the said clamping bars being supported in adjustable relation with respect to each other. 70

8. In a device of the character described, the combination of the casing of a tank for developing photographic films, a holder for receiving and holding a film pack casing, one side of said holder being provided at one end with a hinged extension, said extension having at its outer edge means for engaging one end portion of one side of the film pack casing and the said extension being also provided at its outer edge with a rod tapering from its center toward its opposite ends under which the films travel 85
80 as they are drawn from the film pack casing, cams situated within the casing of said tank and means upon the said extension for engaging the said cams as the said holder is inserted within the said tank casing, substantially as and for the purpose described. 90

9. In a device of the character described, the combination of the casing of a tank for developing photographic films, a holder for receiving and holding a film pack casing 95
95 containing films which holder is adapted to be inserted into the said tank casing, one side of said holder being provided at one end with a hinged extension, said extension having hooks at its outer edge for engaging the opposite edges of one end of a side of the said film pack casing, a rod secured to the outer end of the said extension and being substantially in parallel relation to the edge of said extension, said rod being thickest at 105
100 its center and tapering toward its opposite ends, means situated within the said tank casing and provided with cams, means upon the said extension for engaging the said cams, said cams being of a shape to cause 110
110 lateral inward and outward movement of the said extension as the said holder is inserted into the said tank casing and a device also adapted to be inserted within the said casing in operative relation to the said holder, said device being adapted to receive the films as they are withdrawn from the film pack and hold the same separately and in spaced relation to each other, substantially as described. 115

10. In a device of the character described, the combination of the casing of a tank for developing photographic films, a holder for receiving and holding a film pack casing containing films which holder is adapted to 120
125 be inserted into the said tank casing, one side of said holder being provided at one end with a hinged extension, said extension having hooks at its outer edge for engaging the opposite edges of one end of a side 130

of the said film pack casing, a rod secured to the outer end of the said extension and being substantially in parallel relation to the edge of said extension, said rod being 5 thickest at its center and tapering toward its opposite ends, means situated within the said tank casing and provided with cams, means upon the said extension for engaging the said cams, said cams being of a shape 10 to cause lateral inward and outward movement of the said extension as the said holder is inserted into the said tank casing and a device also adapted to be inserted into the said tank casing which device is adapted 15 to receive and hold the films as they are withdrawn from the said film pack casing, the said device comprising two sets of curved adjustable clamping bars, the said sets of clamping bars being supported in 20 adjustable relation with respect to each other and the said films being adapted to be inserted between adjacent clamping bars of each set and each film being in extended 25 position between the said sets of clamping bars within the said tank, substantially as described.

11. In a device of the character described, the combination of the casing of a tank for developing photographic films, a device 30 adapted to be inserted within the said casing for holding the films in spaced relation to each other, said device comprising two sets of holding means and means for adjustably supporting the said two sets of holding means in opposing relation with 35 respect to each other.

12. In combination, the casing of a tank for developing photographic films, a device adapted to be inserted within said casing 40 for holding the films in spaced relation to each other, said device comprising two sets of holding means, one of the said sets being fixedly secured to parallel bars and the other of said sets being adjustably secured on said bars, substantially as and for 45 the purpose described.

13. In combination, the casing of a tank for developing photographic films, a device 50 for holding the said films in spaced relation with respect to each other, said device being adapted to be inserted into the said casing and the said device comprising a frame, parallel rods to which the said frame is stationarily secured, clamping bars mov- 55 ably supported upon the said frame, a movable frame also supported upon the said parallel rods, clamping bars movably mounted upon the said frame, means for adjusting and holding the said last mentioned bars in clamping relation with respect to each 60 other, substantially as and for the purpose described.

14. In combination, the casing of a tank for developing photographic films, a device 65 adapted to be inserted in the said casing,

which device is adapted to receive and hold photographic films in spaced relation to each other, said device comprising a bail-like member, a frame fixedly secured to the lower free ends of said bail-like member, curved 70 clamping bars movably supported upon the said frame, yielding means for holding the said curved bars in holding relation with respect to each other, a plate movably supported upon the sides of said bail-like member, said plate having a relatively large 75 central opening extending therethrough, curved clamping bars situated in said opening, means upon said plate for movably supporting said clamping bars at their opposite ends, and cam actuating means for moving and holding the said curved bars in clamping 80 relation to each other to hold films in spaced relation with respect to each other, the upper ends of said films being clamped 85 between said last mentioned bars and the lower ends of said films being clamped between the first mentioned bars, substantially as described.

15. The combination of the casing of a 90 tank for developing photographic films, a holding device for the said films, which device is adapted to be inserted into the said casing, the said device comprising two sets of adjustable clamping bars, one of which 95 sets when in operation and in position within the tank occupies a position adjacent the bottom of said tank and the other one of which occupies a position at the top of said tank and constitutes a light proof cover or 100 lid for the said tank.

16. The combination of the casing of a tank for developing photographic films, a light proof lid for said tank, which lid comprises adjustable holding bars for holding 105 the upper ends of the films while the same are being developed and a set of holding bars having adjustable connection with the said light proof lid, said second-named set of holding bars engaging the lower ends 110 of the films, the said two sets of holding bars operating to hold the films in spaced relation to each other.

17. The combination of the casing of a tank for developing photographic films, a 115 light proof lid for said tank comprising a set of adjustable holding bars for holding the upper ends of the films, a lower set of holding bars, a member having fixed connection with the said lower set of holding 120 bars and slidale connection with the first named set of holding bars, substantially as described.

18. The combination of the casing of a tank for developing photographic films, a light proof lid for said tank into which lid is 125 adjustably built duplicate registering sets of holding and spacing bars, the upper set of said spacing bars being a permanent essential part of the light proof lid of the

said tank, the lower or internal set of spacing and holding bars being attached to a bail or handle which slides through openings in the said light proof lid, said bail 5 or handle being adapted to be moved downwardly to move the lower or internal set of holding and spacing bars downwardly after the said light proof lid has been placed in position to close the said tank, said bail 10 or handle extending outwardly from the said tank into position to be manually oper-

ated for moving the internal set of holding and spacing bars downward between the films to the lower edges of the latter, the said films being by the said two sets of holding and spacing bars securely held and spaced at their opposite ends. 15

In testimony that I claim the foregoing as my invention, I have hereunto signed my name this 20th day of August, A. D. 20 1917.

WILLIAM C. MOTTERAM.

Copies of this patent may be obtained for five cents each, by addressing the "Commissioner of Patents, Washington, D. C."
